(57) **CLAIM**

The ornamental design for a support structure for portable electronic device, as shown and described.

DESCRIPTION

This application is related to U.S. Design patent application Ser. No. 29/379,842, filed on Nov. 24, 2010, for Protective Cover with Recessed Edge, and Configured for Use with a Mobile Computing Device, which is a continuation-in-part of U.S. patent application Ser. No. 12/832,845, filed on Jul. 8, 2010, for System and Apparatus for Protecting a Mobile Device, of U.S. Design patent application Ser. No. 29/378, 952, filed on Nov. 11, 2010, for Protective Cover for a Mobile Computing Device, and of U.S. Design patent application Ser. No. 29/379,058, filed on Nov. 12, 2010, for Protective Cover, Including Keyboard, for a Mobile Computing Device, the specifications and drawings of each of which are, by this reference, hereby incorporated herein in their entireties.

FIG. 1 is front perspective view of an embodiment of a support structure for a portable electronic device, the support structure defining a channel configured to receive an edge portion of a portable computing device and orient the portable computing device in an at least partially upright position relative to the keyboard, the channel being connectable to a computing accessory such as a keyboard;

FIG. 2 is a rear view of the embodiment of a support structure for a portable electronic device shown in FIG. 1;

FIG. 3 is a left side view of the embodiment of a support structure for a portable electronic device shown in FIGS. 1 and 2;

FIG. 4 is a top view of the embodiment of a support structure for a portable electronic device shown in FIGS. 1-3;

FIG. 5 is a right side view of the embodiment of a support structure for a portable electronic device shown in FIGS. 1-4; and,

FIG. 6 is a front view of the embodiment of a support structure for a portable electronic device shown in FIGS. 1-5.

None of the features shown in phantom, including, without limitation, the illustrated embodiment of a portable electronic device in FIG. 1 and portions of the support structure shown in phantom in FIGS. 1-6, form any part of the claimed design.

1 Claim, 2 Drawing Sheets
